UNITED STATES PATENT OFFICE.

BERNARD G. VIGURS, OF STATEN ISLAND, NEW YORK.

PIN CLIP.

Application filed September 22, 1922. Serial No. 589,874.

To all whom it may concern:

Be it known that I, BERNARD G. VIGURS, a citizen of the United States, residing at Staten Island, in the county of Richmond 5 and State of New York, have invented certain new and useful Improvements in Pin Clips, of which the following is a specification.

My invention relates to improvements in 10 pin clips, and has for an object to provide a pin clip, that may be used either as a pin or as an ordinary paper clip.

A further object of my invention is to provide a pin clip, which may be used as a pin 15 and as a clip at the same time, and wherein, as a pin clip, it makes a more complete and better means for fastening papers together than a pin or clip alone, as it combines the advantages of both at the same time.

20 A still further object of my invention is to provide a pin clip, whereby when in use, the pin prevents the middle sheets from slipping out of alignment with other sheets or from slipping out altogether as often happens when the ordinary clip is used alone.

25 A still further object of my invention is to provide a pin clip, whereby it is impossible for the top sheets to break loose as it often happens when an ordinary pin is used, and furthermore, there is no head to stick into the end of the user's finger as ordinarily occurs.

30 A still further object of my invention is to provide a pin clip, that has in addition to the above mentioned advantages, to provide means whereby it can be used as a price card or tag support.

35 A still further object of my invention is to provide a pin clip, that is strong, durable, simple and inexpensive in construction, and that is well adapted to the use for which it is designed.

40 Other objects and advantages of the invention will become apparent during the course of the following description.

In the drawings, wherein like numerals are employed to designate like parts throughout the same,

45 Figure 1 is a front elevation of my improved pin clip, when used as a price card or tag support,

50 Figure 2 is a rear elevation of the same, and

55 Figure 3 is a detail perspective of one of my pin clips.

In the drawings, wherein for the purpose

of illustration is shown a preferred embodiment of my invention the numeral 5 designates my improved pin clip in its entirety.

In its construction, my device is made 60 from a single piece of material, and is formed in various designs and patterns and preferably of a non-rusting material. The piece of material is bent at 6 to form the longitudinal member 7, whose length is a little over half the width of the entire clasp 65 pin 5. The material is then bent diagonally forming the arm 8, which is of any desired length, according to the size of the pin clip which is being formed, and is bent at a point 70 9, preferably at right angles to the arm 8, forming a leg 10 which is shorter than the arm 8. The material is then bent at a point 11 and a similar leg 12 is formed the same length as the leg 10, at which point 13, the 75 material is again bent at preferably right angles forming an arm 14 similar to the arm 8, and the material is again bent at a point 15 forming a longitudinal member 16 which is bent at the center of the pin clip, 80 and a pin member 17 is formed, extending a substantial distance below the point 11, said pin member 17 being provided with a point 18.

The arm 8 due to the tension given the 85 same by the arm 14, is held in close contact with the pin member 17 and the point 19, so that the pin clip will form a very efficient paper clip. The length of the pin member 17 would be sufficient to enable the clip to 90 slip completely on to papers, whereby the papers are held in such a manner, that the middle sheets are guarded against slipping out of alignment with the outer sheet or from slipping out altogether, as often happens with the ordinary paper clip now in use. My improved paper clip, may be used as a price card, or tag support, and in such cases, a tag or card 20 is inserted between the pin member 17 and the face of my pin 100 clip, and the pin member 17 is stuck into the body of material on which the price card is placed. It will thus be seen that I have devised a device, which may be used either as a pin or clip, or may be used as a 105 pin and a clip at the same time, but at all events has decided improvements over the ordinary pin clip now in use. In fact it more than combines the advantages of both the pin and the clip, as there is no head to 110 penetrate the skin of the person applying my clip, nor is there any possibility of the

top sheet of paper or other material, being lost when my improved pin clip is being used to fasten several sheets together.

It is to be understood that the form of my invention herewith shown and described is to be taken as a preferred embodiment of the same, and that various changes in the shape, size and arrangement of parts may be resorted to, without departing from the spirit of my invention or the scope of the subjoined claims.

Having thus described my invention, I claim:

1. A pin clip of the class described comprising a vertical shank provided at its lower end with a piercing point, the other end thereof being bent to provide a clamping member including a portion extending across the shank and arranged in contact therewith, and also a second portion extend-

ing across the first named portion to hold the latter in close contact with the shank.

2. A pin clip of the class described comprising a vertical shank provided at its lower end with a piercing point, the opposite end thereof being formed into a clamping member, consisting of a triangular-shaped loop, and a diamond shape loop depending therefrom and arranged parallel with the shank, the lower end of the diamond shaped loop and the portion of the clamp member at the juncture of said loops being arranged in contact with the shank.

In testimony whereof I affix my signature in presence of two witnesses.

BERNARD G. VIGURS.
